UNITED STATES PATENT OFFICE.

JOHN B. BUSHNELL, OF BERKELEY, CALIFORNIA, ASSIGNOR TO BUSHNELL MANUFACTURING CO. INC., OF BERKELEY, CALIFORNIA, A CORPORATION OF CALIFORNIA.

DIE-CASTING MACHINE.

Application filed October 2, 1922. Serial No. 591,713.

To all whom it may concern:

Be it known that I, JOHN B. BUSHNELL, a citizen of the United States, and a resident of the city of Berkeley, in the county of 5 Alameda and State of California, have invented a new and useful Die-Casting Machine, of which the following is a specification.

My invention relates to a machine for 10 making castings in dies. Machines of this general character and their mode of operation are now well known. The advantages of making castings by permitting the metal or alloy to flow into a space defined by a 15 metal die, are quite numerous, and include the obvious ones for example that the castings are maintained accurate to dimensions to a comparatively high degree and also that there is no need for patterns or the like. In 20 fact, the castings are in many instances so accurately formed by this process that little if any subsequent machine finishing is required. With machines as heretofore made, it has been necessary to construct compara- 25 tively expensive dies, and this fact has contributed in preventing the widespread adoption of die-casting. It is obvious that the less expensively these dies may be constructed, the more universal becomes the use 30 of such machines, even if there be slight additional complications needed in the machine itself. It is one of the objects of my invention to supply a die casting machine in which some of the complications of the 35 die construction may be obviated.

The dies in such machine are usually made in parts, which are disposed on relatively movable portions of the machine, for facilitating the extraction of the completed casting. For this purpose, there is provided a 40 movable carriage for one of the die parts. These die parts must be accurately aligned before the metal is poured in, and where the dies are heavy, the stress on the carriage or 45 support may strain the structure sufficiently to produce displacement between the parts of the die. It is thus another object of my invention to provide a simple and accurate form of adjustment for aligning the parts of 50 the die.

Upon bringing the parts of the die together it is essential to provide a tight joint between them, and for this purpose a considerable force must be exerted. This joint 55 must be sufficiently tight to prevent it being

affected by the tendency of the metal within the die to expand the parts. This tendency is quite pronounced where the metal is squirted into the die under pressure. A toggle link, manually operated, is usually utilized to effect the tightening of the joint, but under such circumstances it is necessary for the operator to exert an exhausting stress on the toggle. With the aid of my invention, it is possible to urge the die parts very strongly 60 together without the necessity of excessive effort on the part of the operator.

It is still another object of my invention to provide an extractor for the completed casting, which extractor is made part of the 70 machine and may be used with any of the dies. It is thus unnecessary to provide an extractor mechanism for each die.

As each casting is made by the die, a sprue is formed that usually must be cut away before the casting can be removed. It is another object of my invention to provide a 75 sprue cutter that is adjustable in such a way as to be applicable to any die used in the machine.

In order to force metal into the die, a movable metal container in the form of a gooseneck is usually employed, one end of which may be made to communicate with the sprue hole of the die, and the other to be 85 connected to a source of air pressure. The gooseneck is arranged to be dipped into a reservoir of metal kept in a molten state, and to be raised with its charge of metal so as to permit the die to be filled therefrom. It is 90 another object of my invention to provide a simple and quick control for the movements of this gooseneck.

In connection with some of the dies, it is necessary to use cores which must be extracted after the casting is made. This extraction requires a good deal of force due to the contraction of the metal around the cores. It is another object of my invention to provide a power operated core puller, 100 adaptable either for pulling straight cores, or for the removal of threaded cores that are used for producing tapped holes in the casting.

My invention possesses other advantageous 105 features, some of which, with the foregoing will be set forth at length in the following description, where I shall outline in full that form of the invention which I have selected for illustration in the drawings accompany- 110

ing and forming part of the present specification. In the drawings I have shown but one embodiment of my invention, but it is to be understood that I am not to be limited thereto, since the invention as expressed in the claims may be embodied in other forms as well.

Referring to the drawings:

Figure 1 is a side view of a complete machine embodying my invention;

Fig. 2 is a central longitudinal sectional view of the complete machine;

Fig. 3 is a top plan view of the same;

Fig. 4 is a sectional view taken along the line 4—4 of Fig. 3;

Fig. 5 is a sectional view taken along the line 5—5 of Fig. 3;

Fig. 6 is a cross sectional view of the machine, taken along the line 6—6 of Fig. 2;

Fig. 7 is another cross sectional view taken along line 7—7 of Fig. 2;

Fig. 8 is an enlarged section of the machine showing some of the sprue cutter and casting extractor details;

Fig. 9 is an enlarged section along line 9—9 of Fig. 8;

Fig. 10 is an enlarged view of the sprue cutter, showing the arrangement for adjustment thereof;

Fig. 11 is an enlarged section along line 11—11 of Fig. 1, showing how the carriage may be adjusted;

Fig. 12 is an enlarged plan view of the eccentric connection for the control of the gooseneck; and

Fig. 13 is a diagrammatic view of the power control for the pulling of the cores.

In general the die casting machine includes a structure made up of a pair of relatively movable parts, to which the die halves may be attached. Thus the stationary head 21 is adapted to carry the die half 22, while a movable head 23 carries the other die half 24. The stationary head 21 may conveniently be formed integral with the side of a furnace 25 for heating the metal used in casting. In Fig. 8 the die halves 22 and 24 are shown moved together in a position ready for casting, and in order to move the die half 24, the movable head 23 is carried by a wheeled carriage 25'. The wheels 26 of the carriage may be appropriately guided on a plurality of rails 27, in the present instance shown as bars of round cross section.

The rails 27 are shown as supported at one end by the standard 28 by the aid of the nuts 29 engaging threaded portions of the rails which extend through appropriate apertures in the standard. At the other end these rails 27 may extend into and be supported by the stationary head 21. If necessary or desirable an intermediate standard 30 may be used to prevent undue strains in the rails 27.

The stationary portion 22 of the die may be fastened as by bolts to the head 21. Since

the manner of fastening forms no part of my invention, it is unnecessary to describe it further. The head is provided with an aperture communicating with the interior of furnace 25, and in alignment with this aperture is the sprue forming member 31 of the die half 22, and in this way the metal may be supplied to the die directly from the furnace 25, in a manner that will be described in greater detail hereinafter.

The movable die half 24 is likewise appropriately fastened to the movable head 23, and is designed to interengage with the stationary die half 22, upon movement of the carriage 25' to the position shown in Fig. 8.

This carriage is made up of appropriate parts to form a box-like structure with four upper wheels and four lower wheels for guiding its movement on the rails 27. The movement of this carriage is effected by a toggle mechanism operated manually. The toggle is formed of the links 32 and 33. The link 32 is forked as shown most clearly in Fig. 3, and two links 33 are used, one in each fork.

These links 33 are appropriately pivoted on the rear of the carriage 25', in the lugs 34 fastened thereto. In order to accommodate the machine for varying sizes and thicknesses of dies, the pivoted end of forked link 32 is carried on a longitudinally adjustable plate 35, which slides upon the rails 27. This plate is held in adjusted position by means of the stud 36 which passes through an aperture in the standard 28, and is held in rigid relation therewith by the nuts 37. With this construction only a pair of nuts need be unfastened and refastened for an adjustment.

The toggle is manually straightened and broken by the aid of spoke wheel 38, which is fastened to a shaft 39 carrying the pivot for the forked link 32. The construction of the pivot arrangement for the link 32 is shown most clearly in Figs. 3, 4 and 5. This construction is such that the shaft 39 may be clutched to the forked link 32 for rotating this link, so that the toggle may be straightened and the carriage 25' urged to the right in Fig. 3 so as to bring the two die heads very near each other. However, after the toggle is brought substantially to a straight position, I am enabled, with my device, to urge the pivot of link 32 still further to the right with a great leverage, and thus clamp the die halves securely together.

For the purpose of providing the closing movement, the shaft 39 has an eccentric portion 40 upon which fits the link bosses 41. A key 42 is slidable in a slot 43 in the portion 40, and is urged in one direction by means of a spring 44 disposed in the hollow portion of shaft 39. The key 42 is attached to a guided push rod 45 passing through the

130

- shaft 39. The shaft is journaled for rotation in the ears or bosses 46 of the stationary member 35. The link bosses 41 have a space between them sufficiently long to accommodate the key 42, but under the influence of spring 44, this key may be urged into a keyway 46' formed in the left hand boss 41, provided the key and keyway are in alinement. The initial movement of the toggle is effected while the key 42 is in the keyway 46', so that clockwise rotation of the spoke wheel 38 causes a corresponding rotation of the link 32. After the toggle is straightened, the key 42 is manually disengaged from the keyway 46' by the aid of push rod 45. The spoke wheel 38 is then rotated still further and this causes the eccentric portion 40 of the shaft 39 to rotate within the bosses 41. This in turn urges the center of the bosses 20 in the direction in which the eccentric center is moved; and since the eccentricity may be made comparatively small, a great leverage may be exerted by this means for urging the dies together. The rotation of the portion 25 40 about an eccentric center thus serves the very useful purpose of multiplying a relatively small force applied at the spoke wheel 38. It has been found that no difficulty is obtained with this arrangement to make an 30 oil-tight joint between the die halves. In order to separate the dies, it is merely necessary to rotate the spoke wheel 38 in a counterclockwise direction. The first part of the rotation serves to bring the key 42 into 35 alinement with the keyway 46' and when this occurs the spring 44 causes engagement between them. From that point on, the link 32 is clutched to the shaft 39 and continued rotation simply breaks the toggle.
- 40 After the die halves have been brought together to the position shown in Fig. 8, the metal is introduced through the sprue forming member 31. To do this, a gooseneck 47 is adjustably supported within the furnace 25, whereby it may be dipped into the molten metal 48 in the pot 49 and afterward have its small end brought into registry with the sprue opening. By dipping the gooseneck into the pot 49, it becomes filled, and 50 the capacity of this gooseneck is made large enough to take care of the maximum size of castings handled by the machine. Appropriate means for heating the pot 49 may be provided near the base of furnace 25. After 55 the small end of the gooseneck 47 is brought into the position of Fig. 2, air under pressure may be admitted through pipe 50 at the large end of the gooseneck.
- The gooseneck 47 is fastened to a strip 51 which extends exteriorly of the furnace 25 and is guided in a guide or carrier 52. This carrier is appropriately slotted for the accommodation of the strip 51, and for guiding the gooseneck in its vertical movement for taking up a charge of the molten metal
48. This vertical movement is effected by the aid of a counterweighted lever 53, pivoted at 54 to a pin 55 which in turn is pivoted on a vertical axis in a bracket 56 attached near the top of the furnace. The lever 53 is attached by links 57 to the strip 51, so that upon rotation of the lever about its pivot 54 the gooseneck is moved vertically. The pivoted pin 55 and links 57 permit the gooseneck to have lateral movement toward and from the sprue forming member 31, and the lever 53 is furthermore arranged in a diagonal line for convenience of operation.
- The lateral movement of the gooseneck 47 is effected by moving the guide 52 in a horizontal direction. For this purpose the guide carries a boss or projection 58 which enters into a socket 59 in a carrier 60. This carrier is slidable in a horizontal direction in a guide 61 extending to the exterior of the furnace 25. I preferably employ a toggle connection for moving the carrier 60, and this toggle is arranged to be manually operated by a lever 62. This lever rotates one of the links 63 of the toggle about the stationary axis of shaft 64. The other member of the toggle is made up of a pair of levers 65 connected to the movable carrier 60 by means of a pin 66. This pin is pivoted in the links 65 and has an eccentric portion 67 upon which the carrier 60 is pivoted. This is shown most clearly in Fig. 12. Upon straightening the toggle, it is possible to apply a still greater force to urge the small end of gooseneck 47 against sprue forming member 31 by rotating this pin. This is most conveniently effected by the aid of a rod inserted in any of the apertures in the head 68 of the pin 66. The rotation of pin 66 should be toward the left as seen in Fig. 3 to tighten the connection, and in the opposite direction to loosen it.
- With these controls of the gooseneck, it is possible to move it quickly into the metal 48, withdraw it after it is charged, and bring it into registry with the sprue forming member 31. After this is accomplished the air is admitted through the armored cable 69 leading to an air control box 70. After the die is filled with the metal and it has cooled sufficiently, the air pressure is released, and the gooseneck is moved away.
- The die halves are usually so arranged that the sprue or waste metal, filling the inlet to the die, may be cut away and allowed to return into the pot 49. For this purpose there are alined apertures designated at 71 in Fig. 8 in the die halves, which apertures form the sprue and extend entirely through both die halves. The back end of this aperture is closed by a sprue cutter 72 comprising an axially movable round bar arranged to slide in the apertures 71. When this bar or cutter is forced through the die halves,

the sprue is cut and ejected into the furnace 25 through an opening 73 in the stationary plate 21. The movement of the cutter may be effected by the aid of a pinion 74 rotatable about a pivot 75 in a bracket 76. This bracket is attached to the rear plate 77 of the carriage 25. The pinion 74 engages with a rack 78 which is of square cross section as shown in Fig. 9, and is slideable within the bracket 76. The sprue cutter 72 is adjustably held within a groove 79 cut in the rack 78, and for this purpose a strap 80 is used, which engages one of a series of necks or slots 81 in the sprue cutter. These slots are shown most clearly in Fig. 10. It is thus evident that the position of cutter 72 may be adjusted by unfastening the strap 80 from the top of the rack, and moving the cutter until another of the notches or slots 81 is in position to be engaged by the strap 80. This strap may then again be tightened by aid of screws 82. The adjustment of the length of the sprue cutter is necessary in order to take care of the varying widths of the dies handled by the machine, and thus to provide for the complete removal of the sprue after it is cut. It is not essential to have a fine degree of adjustment of this length, since it is merely necessary to make sure that the sprue cutter extends at least entirely through the die upon complete movement of the rack 78. This movement is effected by the aid of a handle 83 attached to the pinion 74. The sprue cutter 72 is furthermore guided in its axial movement by a hollow tubular member 84 which is shown as supported upon the rear of the movable head 23, by the aid of the threaded portion 85. From the foregoing description, it is evident that movement of the handle 83 of Fig. 1 in the direction of the arrow causes the sprue cutter 72 to be moved to the right and thereby to cut the sprue and expel it.

After the sprue is cut by the means hereinbefore described, the casting itself may be removed from the die. For this purpose the die halves are separated by the aid of the spoke wheel 38. Ordinarily the die halves are so arranged that the movable portion 24 retains the casting. In dies as heretofore made, each is supplied with a manually operated device for extracting the casting from the movable half, and the entire mechanism is duplicated for each die. With the aid of my invention, such duplication is avoided in a great measure; it is merely necessary to provide on each die an arrangement shown somewhat diagrammatically in Fig. 8. This arrangement consists of a plate 86 held on posts 87 which slide within the die half 24 and serve, when plate 86 is moved to the right, to engage the casting within the die and extract it. The movable head 23 may be apertured for the accommodation of these posts 87.

Furnished with the machine itself is a device for moving the plate 86, and in the embodiment shown this device includes a rack and pinion movement. The rack 88 is stationary and is conveniently formed on the under side of the tubular member 84. The pinion 89 is rotatably supported in bracket 90 slideable upon the member 84, which thus serves also as a guide for this bracket. To the shaft 91 of the pinion 89 is attached a lever or handle 92. When this handle is pulled in the direction indicated by the arrow of Fig. 2, the entire bracket is moved to the right. The bracket 90 has a plurality of apertures 93, 94 which are adapted to accommodate the rods 95. These rods engage the extractor plate 86 and are adjustably held to the bracket 90 by the aid of the nuts 96 which engage the threaded portion of the rods 95. The engagement between these rods and plate 86 may also be a threaded one. In order to facilitate the insertion of these rods into the threaded apertures in the plate 86, they may be flattened as at 97 for convenience in turning. Due to the provision of the long apertures 93, it is possible to make the rods 95 fit varying sizes of plates 86. From the foregoing description, the operation of the extractor device is apparent.

In many instances before the casting can be extracted, it is necessary to remove cores which have been inserted within the die in a direction perpendicular to the movement of the carriage 25. Where there are more than one core to be pulled, to do so by hand is a long process. With the power core puller shown, four cores may be pulled simultaneously by power. In Fig. 8 I show a straight core 98 and a threaded core 99 within the die half 24. This threaded core is used for producing a tapped hole in the casting. The pulling of core 98 is effected by the aid of a rack and pinion arrangement, which is shown in greater detail in Figs. 7 and 8. In these figures I show three separate rack arrangements for pulling three straight cores and a fourth for pulling the threaded core 99. However, since all three of the straight core pulling devices operate on substantially the same principle, I shall describe but one of them in detail. Furthermore the number of core pullers needed depends upon the particular die used, and it is possible to substitute for any of the straight core pulling devices, a threaded core pulling device, or vice versa.

To pull the core 98, then, I employ a rack 100 having at its ends a threaded socket 101 or the like by means of which it may be attached to the core 98. The rack 100 meshes with a pinion 102 which is splined to a shaft 103, so as to permit only relative axial movement between the shaft and pinion. This shaft is supported on a bracket 104 which is

fastened by means of bolts 105 to the movable head 23. These bolts engage long slots 106 in the head, thereby permitting adjustment of the core puller in a direction transverse to the movement of the die halves. The shaft 103 supports the guide 107 for the rack 100. This guide is slideable along the shaft 103, and is prevented from rotating by the engagement of the socket portion 101 of the rack 100 within the die head. The arrangement is such that this end of the rack is never entirely withdrawn from the die head, even if the core is pulled out of the casting entirely. I provide an arrangement 15 for driving the shaft so as to reciprocate the rack and for this purpose at the front end of the bracket 104, the shaft 103 also carries a crank 108. This crank is keyed to the shaft. A drum 109 is free to rotate over the shaft, and is shown as enclosing the crank 108. To the drum is attached a sprocket wheel 110. For causing the drum to drive the shaft, I provide shoes 111 and 112, fastened by bolts 113 on the inside of the drum 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

then there would be no opposition to a bodily rotation of the rack about the axis of shaft 103. To effect this result, then, the shoe 120 is made to engage the crank 121 of drum 116 first, and afterward the other 70 cranks engage at the proper time so that all of the cores will end their outward movement simultaneously. The insertion of the cores is effected by the engagement of the other shoes 113, 122 and 123 when the direction of the drive is reversed.

The power arrangement is diagrammatically illustrated in Fig. 13, where mains 124 form a source of either A. C. or D. C. electric power, supply current to the motor 118 80 through connecting devices 125 and 126. These devices may be arranged to be automatically operated to disconnect the motor in response to the completion of the core movement, but for the sake of simplicity they are 85 merely shown as manually operated switches. The particular mechanical connection between the motor shaft and the sprocket wheels or chain is of no especial importance, and in the present instance it is shown diagrammatically as comprising a small 90 sprocket wheel 127 directly on the shaft of the motor and engaging the chain 119.

In some instances, as mentioned heretofore, the core to be pulled is a threaded one, and therefore to pull it requires a slightly modified form of apparatus in place of the rack 100 and pinion 102. Such a modified arrangement is shown in connection with the drum 115 of Figs. 7 and 8. The shaft 128 100 in this instance rotates a bevel gear 129 which is fastened to the shaft 128. This gear in turn serves to rotate the bevel gear 130 and the rod 131. This rod is splined to the sleeve 132 fixed to the gear 130 so as to allow relative axial movement. The core to be pulled is connected with rod 131 which serves to rotate it out of the casting in the die, or to insert it into the die. A support 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

Before any great success can be attained with die casting, it is necessary to insure correct alinement of the die halves. This is especially necessary where the dies are heavy 115 and cause deflections or strains in the various supporting elements for the dies. In the present instance I show a scheme whereby the die halves may be very accurately alined. For this purpose the carriage 25 is made adjustable in either a vertical or horizontal direction with respect to the stationary head 12. How this adjustment is effected in the present instance is illustrated in Fig. 1, 120 which shows one of the roller mountings on the carriage. The carriage is supported upon a stout pin 133 which may be adjusted in the aperture 134 of the carriage. By sliding this pin axially within the aperture 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945

the adjustment may be secured by the aid of the set screw 135 held in the carriage 25. All four of the rollers may be thus adjusted until the proper horizontal position of the carriage 25 is obtained.

For securing vertical adjustment of the carriage, that portion 136 of the pin 133 which carries the roller 26 is made eccentric to the other portion. In this way a slight 10 rotation of the pin within the aperture 134 serves to vary the height of the carriage 25. Both adjustments are made while the carriage is held off the rails 27 by any appropriate means.

15 The mode of operation of the entire machine may now be summarized. After the die halves 22 and 24 have been accurately set up in the machine, they are coated with an oil solution so as to prevent the casting 20 from sticking. The carriage 25 is now operated to move toward the furnace end, by the aid of the spoke wheel 38. The eccentric shaft 40 is then disengaged from the link 32, and the shaft 39 revolved by the wheel 38 to effect an oil tight joint between the die 25 halves. The cores may now be inserted by the aid of the motor 118, and the air within the die is exhausted in any well known manner. The gooseneck 47 is charged with metal 30 by dipping it within the pot 49, with the aid of lever 53. The lever 62 is then operated to bring the gooseneck into registry with the sprue hole of the die and into the position of Fig. 2. The pin 66 is rotated to seal 35 this connection. Air under pressure is now admitted through pipe 50 and the metal is squirted thereby between the dies. The pressure is then released, and the gooseneck 47 is moved away. The sprue cutter 72 is 40 now operated by the aid of lever 83, and the sprue is ejected into the pot 49. The cores if there are any are then pulled by starting motor 118. The carriage 25 may 45 now be brought to open position by the aid of spoke wheel 38. To extract the casting, the lever 92 is operated, which causes the plate 86 to push the posts 87 into the die half 24, and engage the casting.

With the aid of my machine, dies of 50 widely varying form may be accommodated and easily used. This is due to the various adjustments I provide, as in the sprue cutter and core puller. Furthermore the movement of the carriage and sealing of the die 55 halves is effected without undue effort by the aid of the eccentric arrangement in the toggle mechanism.

I claim:

1. In a die casting machine, a stationary 60 die head, a carriage, a movable die head fastened to the carriage, a guide for the carriage, and means for adjusting the carriage with respect to its guide.
2. In a die casting machine, a stationary 65 die head, a carriage, a movable die head fas-

tened to the carriage, rollers for the carriage, and means for adjusting the center of the rollers with respect to the carriage.

3. In a die casting machine, a stationary die head, a carriage, a movable die head fastened to the carriage, rollers for the carriage, and a shaft for the rollers, said shaft having an eccentric portion adjustably held in the carriage.

4. In a die casting machine, a stationary 75 die head, a movable die head, and means for urging the heads toward each other, comprising a lever for causing the initial movement, and means acting on one end of the lever for producing a relatively small movement.

5. In a die casting machine, a pair of relatively movable die heads, a toggle for moving the heads relatively to each other, and a shaft having an eccentric portion forming 85 the pivot point for one of the toggle members.

6. In a toggle mechanism, a link forming one of the toggle members, and a shaft having an eccentric portion forming the pivot 90 point for the link.

7. In a die casting machine, a pair of relatively movable die heads, and means for moving the heads relatively to each other, comprising a lever, a rotatable shaft having 95 an eccentric portion upon which the lever is supported, and means for mechanically clutching and unclutching the shaft and lever.

8. In combination, a lever, a rotatable 100 shaft having an eccentric portion upon which the lever is supported, and means for mechanically clutching and unclutching the shaft and lever.

9. In a die casting machine, a pair of 105 relatively movable die heads, toggle links for moving the heads relatively to each other, a shaft having an eccentric portion serving as one of the link pivots and a sliding key on the eccentric portion adapted to 110 be moved into a keyway formed in the link.

10. In combination, toggle links, a shaft having an eccentric portion serving as one of the link pivots, and a sliding key on the eccentric portion adapted to be moved into 115 a keyway formed in the link.

11. In a toggle mechanism for operating the movable die head of a die casting machine, a link for the toggle having a bifurcated portion, a stationary shaft having an 120 eccentric portion passing through the bifurcations, a key slidable in the eccentric portion between the bifurcations, a spring in the shaft urging the key toward one of the bifurcations, said bifurcations having a keyway in which the key may slide when in alignment, means for rotating the shaft, and means for urging the key in a direction away from the keyway.

12. In a die casting machine, means for 130

- extracting the casting from the die comprising a die head, a guide having a rack cut therein, said guide being arranged in back of the die head, a member slidably supported by the guide, a pinion rotatably supported on the member and meshing with the rack, and means for rotating the pinion.
13. In a die casting machine, means for extracting the casting from the die comprising a die head, a movable plate supported in back of the head, and posts adjustably mounted on the plate for exerting a pressure against the casting.
14. In a die casting machine, means for extracting the casting from the die, comprising a die head, a plate movably supported with respect to the head, means for moving the plate, and posts adjustably mounted in slots in the plate.
15. In a die casting machine, a container for supplying metal to the interior of the die, and means for controlling the movement of the container comprising a vertical guide for the container and means for moving the guide in a substantially horizontal direction.
16. In a die casting machine, a container for supplying metal to the interior of the die, a vertical guide for the container, and a toggle for moving the guide toward the sprue hole of the die.
17. In a die casting machine, a container for supplying metal to the interior of the die, a lever system for moving the container toward the sprue opening of the die, and a shaft having an eccentric portion forming one of the pivots for the lever system.
18. In a die casting machine, a container for supplying metal to the interior of the die, a toggle link mechanism for moving the container toward the sprue hole of the die, and a pivot shaft for one of the links rotatably mounted on a moving portion of the container, said shaft having an eccentric portion forming the pivot for one of the toggle links.
19. In a machine for making castings in a die having a threaded core, means for moving the core in and out of the die, comprising a rotatable shaft, and a sliding mechanical connection between the shaft and the core.
20. In a machine for making castings in a die having a core, means for moving the core in and out of the die, comprising a rotatable shaft, and a gear connection between the shaft and the core.
21. In a machine for making castings in a die having a core, a rotatable shaft for transmitting a force to the core to move it in and out of the die, and a bearing support for the shaft adjustably mounted on the machine.
22. In a machine for making castings in a die having a core, a rotatable shaft for transmitting a force to the core to move it in and out of the die, and a driven member axially slidably along the shaft and adapted to be connected to the core.
23. In a machine for making castings in a die having cores, a plurality of core pulling means, a single means for moving all of the core pullers, and means whereby the sequence of operation of the pullers may be determined.
24. In a machine for making castings in a die having cores, a plurality of rotatable shafts, a plurality of core pulling means associated with the shafts, a single means for rotating all of the shafts, and means whereby the sequence of operation of the shafts may be determined.
25. In a machine for making castings in a die having cores, a plurality of rotatable shafts, core pullers operated by the shafts, a rotatably mounted member on each shaft, a common means for rotating all of the members, and adjustable projections mounted on each of the members for driving the shaft.
26. In a machine for making castings in a die having cores, a plurality of rotatable shafts, adjustable supports for the shafts, core pullers operated by the shafts, and a common means for rotating all the shafts.
27. In a machine for making castings in a die having cores, a plurality of rotatable shafts, cranks carried by the shafts, core pullers operated by the shafts, a drum rotatably mounted on each shaft, a shoe adjustably mounted in each drum and adapted to coact with the crank, and a common means for rotating the drums.
28. In a die casting machine, a die head, a carriage for the die head, a plurality of guide rails for the carriage, means for moving the carriage, and means for adjusting the extremes of travel of the carriage comprising a member forming a pivot for the moving means, and slidable on the rails, and means for varying the position of the slideable member on the rails.

In testimony whereof, I have hereunto set my hand.

JOHN B. BUSHNELL
